(57) **CLAIM**

The ornamental design for a paddle board safety box, as shown and described.

DESCRIPTION

FIG. 1 is a top perspective view of a paddle board safety box, in accordance with the new, original, and ornamental design; FIG. 2 is bottom perspective view of the paddle board safety box shown in FIG. 1;

FIG. 3 is a front view of the paddle board safety box shown in FIG. 1;

FIG. 4 is a rear view of the paddle board safety box shown in FIG. 1;

FIG. 5 is a left side view of the paddle board safety box shown in FIG. 1;

FIG. 6 is a top view of the paddle board safety box shown in FIG. 1; and,

FIG. 7 is a bottom view of the paddle board safety box shown in FIG. 1.

The broken lines illustrate portions of the paddle board safety box and form no part of the claimed design.
